UNITED STATES PATENT OFFICE.

HENRY E. WAITE, OF NEW YORK, N. Y., ASSIGNOR TO H. C. MINER, TRUSTEE,
OF SAME PLACE.

ELECTRICAL THEATRICAL APPLIANCE.

SPECIFICATION forming part of Letters Patent No. 513,850, dated January 30, 1894.

Application filed August 29, 1893. Serial No. 484,302. (No model.)

To all whom it may concern:

Be it known that I, HENRY E. WAITE, a citizen of the United States, residing in the city, county, and State of New York, have invented 5 certain new and useful Improvements in Electrical Theatrical Appliances, of which the following is a specification.

My invention relates to theatrical appliances adapted to be used in connection with 10 theatrical displays of various kinds, the object being broadly to provide means whereby the actor or performer can readily, easily and quickly, through automatic mechanisms, produce various effects in harmony with or accompanying with the performance, such for 15 instance, as operating musical instruments, moving scenery or mechanical figures, or anything of the kind, and to these ends my invention consists in a construction embodying 20 the general features, substantially as herein-after more particularly set forth.

In the accompanying drawings, I have illustrated so much of an apparatus embodying the general principles of my invention as will 25 enable those skilled in the art to understand and use the same, and Figure 1, is a partial perspective and partial diagrammatic view, showing one way of operating my device. Fig. 2, is a plan view of a portion of Fig. 1; 30 and Fig. 3 is a diagram of one arrangement of part of the circuits, and Fig. 4, is an enlarged sectional view of one form of circuit-controller adapted to be used in carrying out my invention.

35 In theatrical or similar performances, it is often desirable to add to the effect of the performance by incorporating therewith at proper times and in proper relations thereto, certain mechanical, musical or other effects, 40 such as illumination, &c., and it is also desirable to have appliances whereby the performer may readily and quickly bring these adjunctive devices into co-operation with his performance at will, through the means of 45 automatic mechanism, and it is the object of my invention to provide such means, which shall be simple and effective, and capable of being adapted for many and various purposes.

My invention embodies a number of circuit 50 controllers, properly arranged in connection with the stage and having electrical connec-

tions with various devices, whereby the movements or operation of these devices can be controlled by the performer, and I have shown a platform A, which may be a portion of the 55 regular stage, or may be a supplementary portion, and this platform is provided with a number of circuit controllers B. These controllers are arranged so that they project but slightly above the face of the platform, and 60 in such positions that they can be operated by the foot or other portion of the performer. Thus, I have shown a series of push-buttons embedded in the body of the platform, and having electrical connections with the various 65 devices which are to be operated thereby. For instance, the controller B', is connected with a circuit C, including a battery and a musical instrument shown for the sake of simplicity as a bell, and it will be readily understood that any other instrument may be 70 used, and any number of them, the circuit controllers being arranged so that by operating any particular controller a particular sound or musical tone or other signal will be 75 produced. The circuit controllers B², B³, for instance, are connected with an electric circuit C', including a relay D, and the armature of this relay is connected to operate a reversing switch E, controlling a circuit E' of 80 an electro-motor F. The circuit C' in the present instance, is arranged so that on pressing the controller B², the contacts c, c, c', c', will be closed, while on pressing the controller B³, the contacts c², c², c³, c³, will be closed, thus 85 reversing the direction of the current of the battery or generator X, and operating the relay D to move the armature to one extreme or the other of its positions, and thereby remove the pole-changer E, to reverse the current through the motor F. This arrangement of circuits is only given as an example, as 90 any electrician will understand that the circuits can be changed or arranged in any well-known way to produce the desired results. 95 This motor F is shown in the present instance as mounted on or connected with a mechanical figure G, which is shown in a conventional way, and as being provided with rollers g, adapted to run upon a way H, in proper relation with the stage, and it will be seen that 100 the performer, by operating the proper con-

- troller can cause the mechanical figure to move back or forth, and off the stage, or to perform other arrangements, according to the nature of the case. In this instance, I have shown the motor as mounted on the figure and moving therewith, but it is evident that the motor can be stationary and be connected by suitable belts, bands, or otherwise, with the figure.
- 10 While I have shown the circuit connected with the mechanical figure, it is evident that other devices may be substituted; that for instance, the scenes may be shifted; that illuminating effects may be controlled, and in fact 15 any well-known and desirable effect can be produced on or near the stage, automatically by the performer; for instance, some of the controllers can be connected to the instruments of the orchestra, or with other appliances in different parts of the theater or hall while the performance is taking place, and without attempting to enumerate all the adaptations and uses of my invention, I have shown enough to clearly set forth the principles thereof, so that those skilled in the art 25 can readily avail themselves of the benefits of my invention.
- While I have shown push-buttons mounted in the platform, it is evident that other well-known circuit controllers can be used, it only being necessary to provide some simple and effective means so arranged that the performer 30 may readily operate the controllers in a natural and graceful manner, without attracting

too much attention to the movements of the 35 performer in accomplishing this result.

I am aware that it is old to provide printing telegraphs and typewriting devices with a series of banks of key-levers arranged to control electric circuits, which in turn control the various printing mechanisms, and I do not claim any such construction.

What I claim is—

1. In a theatrical appliance, the combination with a platform adapted to support the 45 performer and having circuit-controllers connected therewith adapted to be operated by the foot of the performer, of circuits connected with the controllers, motors operated by said circuits, and devices connected with 50 said motors to be operated thereby, substantially as described.

2. In a theatrical appliance, the combination with a platform and circuit controllers thereon arranged to be operated by the performer, of a track, mechanical appliances mounted on the track, a motor connected with said appliances, and circuits between the circuit controllers and motor, substantially as described.

In testimony whereof I have signed my name to this specification in the presence of two subscribing witnesses.

HENRY E. WAITE.
